UNITED STATES PATENT OFFICE.

JOHN WESTINGHOUSE, OF SCHENECTADY, NEW YORK.

STEAM-BOILER SPARK-ARRESTER.

SPECIFICATION forming part of Letters Patent No. 247,722, dated September 27, 1881.

Application filed June 21, 1881. (No model.)

To all whom it may concern:

Be it known that I, JOHN WESTINGHOUSE, a citizen of the United States, residing at Schenectady, in the county of Schenectady 5 and State of New York, have invented new and useful Improvements in Steam - Boiler Spark - Arresters, of which the following is a specification.

This invention relates to spark arresting or 10 extinguishing attachments to steam-boilers; and it consists in a jacket which incloses the boiler both at the side and top thereof, and which is divided into two compartments for receiving and discharging the smoke, respectively, by vertical partitions terminating above the bottom of the jacket, a damper-bonnet which communicates with the smoke-flue of the boiler and with both compartments of the jacket, and whose damper is arranged to shut 15 off communication with the discharging-compartment of the jacket, and a smoke-stack communicating with the discharging-compartment 20 of the jacket, as hereinafter more fully set forth.

This invention is illustrated in the accompanying drawings, in which Figure 1 represents a side view, partly in section. Fig. 2 is a vertical central section. Fig. 3 is a plan or top view, omitting the top of the jacket, together with the damper-bonnet, and showing the partitions of the jacket. Fig. 4 is a horizontal section of the damper-bonnet on the line *x x*, Fig. 2.

Similar letters indicate corresponding parts.

The letter A designates the boiler; B, the 35 jacket; C, the partitions; D, the damper-bonnet; E, the damper, and F the smoke-stack.

The boiler is in two sections, and its outer vertical shell is united by rings 5 6, which are riveted to the shell-sections, respectively, and 40 bolted or otherwise fastened together.

The jacket B incloses the boiler at the side, on that portion thereof above the joint 5 6, and also at the top; and in order to facilitate the removal of the sparks accumulating in the 45 jacket it is made removable.

The partitions C are arranged diametrically opposite to each other, in vertical positions, dividing the jacket into two compartments, B' B², but the partitions are made to terminate 50 above the bottom of the jacket, as shown in

Fig. 1, so as to establish a communication between the compartments.

The damper-bonnet D is placed at the top of the smoke-flue A' of the boiler, and is partly open at the bottom to communicate with such flue, while it is also open on opposite sides of its damper E, to communicate with both compartments B' B² of the jacket.

The damper E is secured to a horizontal rod, 7, which extends outward through the top part 60 of the jacket B, and is provided with a handle, 8, at its outer end. At the top and bottom of the damper-bonnet D respectively is formed a web, 9 or 10, partially closing the same at those points, and the damper E is so arranged 65 that by turning it in the proper direction its edges may be brought into contact with these webs, as shown in Figs. 2 and 4, which constitutes the closing position of the damper, and whereby the communication of the damper-bonnet with the compartment B' of the jacket 70 is shut off.

The smoke-stack F is connected to the top of the damper-bonnet D in a vertical plane with the smoke-flue A' of the boiler, and it 75 communicates with the compartment B² of the jacket through the opening left at the top of the bonnet.

When the damper E is closed the smoke or products of combustion rising in the boiler-flue 80 A' are received in the compartment B' of the jacket, thence pass around the lower ends of the partitions C into the compartment B², whence they discharge into the smoke-stack F, as indicated by arrows in Figs. 1 and 2, and 85 by this circuitous passage the sparks are either arrested or extinguished, the arrested sparks being deposited in the bottom of the jacket, while when the damper is opened the products of combustion pass directly into the smoke-stack. Another effect of the said passage of the smoke through the jacket is to make the latter a heating-medium, protecting the boiler 90 against the condensing effects of the atmosphere.

What I claim as new, and desire to secure by Letters Patent, is—

The combination, substantially as hereinbefore set forth, with the boiler, of the jacket inclosing the boiler both at the side and top 100

thereof, the vertical partitions of the jacket terminating above the bottom thereof and dividing the same into two compartments for receiving and discharging the smoke, respectively, the damper-bonnet communicating with the smoke-flue of the boiler and with both compartments of the jacket, the damper arranged in the bonnet to shut off its communication with the discharging-compartment of the jacket, and the smoke-stack communicat-

ing with the discharging-compartment of the jacket, all arranged substantially as shown and set forth.

In testimony whereof I have hereunto set my hand and seal in the presence of two subscribing witnesses.

JOHN WESTINGHOUSE. [L. S.]
